UNITED STATES PATENT OFFICE.

RUDOLPH DE BOER, OF GRAND RAPIDS, MICHIGAN, ASSIGNOR TO GRAND RAPIDS METALCRAFT CORPORATION, OF GRAND RAPIDS, MICHIGAN, A CORPORATION OF MICHIGAN.

WALL POCKET.

Application filed August 15, 1927. Serial No. 212,968.

This invention relates to wall pockets and more particularly to wall pockets mounted within enclosed motor cars for use as smoking containers or vanity cases.

5 The main objects of this invention are to provide a container which may be readily mounted on a wall; and further to provide a removable receptacle fitting within the container; and further to provide a removable receptacle spring-pressed in fitting position tensionally held within the container.

An illustrative embodiment is shown in the accompanying drawings wherein:—

10 Figure 1 is perspective front elevation of the assembled wall pocket;

Figure 2 is a perspective view of an insert member; and

15 Figure 3 is a sectional view of the structure mounted on a wall and taken on line 3—3 of Figure 1.

The construction shown in the drawings comprises the container 1 having a rear wall 2, front wall 3 and angularly disposed ends 4.

20 25 An insert member 5 having a back portion 6 and a top portion 7 is adapted to detachably fit within the container, its back portion 6 lying adjacent the inner side of the rear wall of the container. This back portion of the insert member is provided with a pair of bayonet slots 8 which register with a similar pair of bayonet slots 9 in the rear wall 2 of the container. Screws 10 in the wall 11 are provided for mounting the container and its insert member. These screws are spaced to register with the bayonet slots in the rear wall of the container and those in the back portion of the insert member.

30 35 An aperture 12 in the depending lip 13 of the insert member is provided for detachably securing the insert member within its container by a screw 14.

The top portion of the insert member is provided with a rectangular opening 15 from which marginal flanges 16 and spring tensioned lips 17 depend.

40 45 A receptacle 18 having spaced openings 19 in its top for ashes, matches, cigarettes,

or toilet articles is adapted to be removably and tensionally retained within the rectangular opening 15 of the insert member.

It will thus be seen that the wall pocket may be readily assembled and conveniently mounted on the inside wall of a motor car.

I claim:

1. In a device of the class described, a container having a rear wall provided with bayonet slots for securing the container to a wall, an insert member detachably fitting within the container and having a back and top portion, said back portion having bayonet slots adapted to register with the slots in the container and said top portion having an opening therein, and a receptacle adapted to be removably held within said opening of the insert member.

2. In a device of the class described, a container having a rear wall provided with bayonet slots for securing the container to a wall, an insert member detachably fitting within the container and having a back and top portion, said back portion having bayonet slots adapted to register with the slots in the container and said top portion having an opening therein, a spring tensioned lip depending from the inner edge of said opening, and a receptacle adapted to be removably and tensionally held within said opening of the insert member.

3. In a device of the class described, a container having a rear wall provided with bayonet slots for securing the container to a wall, an insert member detachably fitting within the container and having a back and top portion, said back portion having bayonet slots adapted to register with the slots in the container and said top portion having an opening therein, a plurality of spring tensioned lips depending from the inner edge of said opening, and a receptacle adapted to be removably and tensionally held within said opening of the insert member.

In testimony whereof I have hereunto set my hand at Grand Rapids, Michigan, this 29th day of July, 1927.

RUDOLPH DE BOER.
